SHOE COUNTER

Arthur C. Sewall, Richmond, Maine

Application July 7, 1932, Serial No. 621,219

4 Claims. (Cl. 36—77)

My invention relates to counters for shoes, and has among its objects the provision of an improved counter which, among other things, secures all the advantages which have heretofore been secured with counters constructed entirely of leather and all the advantages which have heretofore been secured with those constructed entirely of fiber board, and without securing the disadvantages of either.

10 The invention however will be best understood from the following description when read in the light of the accompanying drawing of a counter constructed according to the invention, the scope of which latter will be more particularly pointed out in the appended claims.

In the drawing:—

Fig. 1 is a perspective of the counter constructed according to the invention;

Fig. 2 is a perspective of a fragment of the strip from which the counter is fabricated; and

Fig. 3 is a section on the line 3—3 of Fig. 1.

Heretofore, shoe counters have commonly been constructed wholly of natural or artificial leather, or wholly of fiber board or like relatively stiff material. A counter constructed wholly of leather, to secure the necessary stiffness at the lower portions of the counter, must be relatively thick, which makes it expensive and makes it difficult to form the flange at the bottom for attaching the counter to the insole and upper. Further, a counter of such thickness, although it may be suitably beveled at its upper edge portion to secure the requisite flexibility at that portion, is rather bulky. In consequence, in practice a whole leather counter is commonly made of leather the thickness of which is a compromise between that which will secure the requisite stiffness at the lower portion and that which is too bulky. The result is an expensive counter which is not altogether satisfactory.

When a counter is made wholly of fiber board or similar material, the counter, due to the relatively great stiffness of such material as compared to leather, may be relatively thin, which facilitates the forming of the bottom flange and eliminates bulkiness while providing an inexpensive construction. However, such a counter cannot be formed to secure the desired flexibility at the upper edge of the counter without resorting to expensive and troublesome softening treatment, and in fact no satisfactory practical method of so treating fiber board has yet been advanced.

According to the present invention, the lower portion of the counter is formed of a strip 1 of

fiber board which may be readily formed to provide the bottom flange 3 of the counter, while the upper portion of the counter is made of a strip 5 of flexible material such as artificial or natural leather, preferably the latter. The 60 leather strip 5 may be much thinner than the fiber strip 1, and much thinner than would be the case if the counter were wholly of leather, satisfactory results being secured, for example, when the fiber strip is of number 12 to number 65 16 fiber gauge and the leather strip is of 3 or 4 irons in thickness. This of course results, among other things hereinafter pointed out, in a reduction in the cost of manufacture.

As shown, the strips 1 and 5 are beveled, as 70 indicated at 7, and are arranged with their edges in overlapping relation with the leather strip on the outer side of the counter, and are cemented together, preferably with flexible rubber cement. Commonly, the upper edge portion of the leather 75 strip may be beveled, as indicated at 9, to a feather edge so as to secure the desirable flexibility at the upper edge portion of the counter, while the lower edge portion of the fiber strip may be slightly beveled, as indicated at 11, to 80 facilitate the forming of the flange 3 and for securing the desired thinness of the edge portion of said flange.

When the strip according to Fig. 2 is molded to form the counter illustrated in Fig. 1, in which 85 the walls are bent to a profile an example of which is indicated in Fig. 3, it has been found that a smooth walled counter results, due to the arrangement of parts as shown by Fig. 2, and that the joining beveled portions 7 of the two strips, 90 due to the increasing amount of leather at the joint as the upper part of the latter is approached, causes a gradual decrease in the degree of flexibility at the joint from that of the fiber board to that of the leather, resulting in a smooth walled 95 bend when the counter is flexed when the shoe is in use. Also it has been found, that with the leather on the outer side of the counter at the joint portion thereof, that portion may be more readily sanded than would be the case if the fiber 100 board were on the outer side to reduce any irregularities that may be present on the outer surface, which irregularities if present would mar the appearance of the finished shoe.

It will be understood that wide deviations may 105 be made from the embodiment of the invention submitted without departing from the spirit of the invention.

I claim:

1. A shoe counter the body of which comprises 110

- a lower strip of relatively stiff fiber board and an upper strip of relatively flexible material, the two strips having overlapping relatively wide beveled portions cemented together to form a wide 5 skived joint at a point intermediate the height of the counter whereby both pieces of material at opposite sides of said joint form part of the side walls of the counter.
2. A shoe counter the body of which comprises 10 a lower strip of relatively stiff fiber board formed at its lower edge portion to provide a bottom flange for the counter, and an upper strip of relatively flexible material, the two strips having overlapping relatively wide beveled portions cemented 15 together to form a wide skived joint at a point on the side of the counter well above said flange whereby both pieces of material at opposite sides of said joint form part of the side walls of the counter.
- 20 3. A shoe counter the body of which comprises a lower strip of relatively thick stiff fiber board formed at its lower edge portion to provide a bottom flange for the counter, and a relatively thin upper strip of flexible material beveled to a 25 feather edge at the top of the counter, said strips having overlapping relatively wide beveled portions cemented together to form a wide skived joint joining said strips at a point on the side of the counter well above said flange whereby both pieces of material at opposite sides of said joint form part of the side walls of the counter, the overlapping edge of the flexible upper strip being at the outer side of the counter.
4. A shoe counter the body of which comprises 30 a lower strip of relatively thick stiff fiber board formed at its lower edge portion to provide a bottom flange for the counter, and a relatively thin upper strip of flexible leather beveled to a feather edge at the top of the counter, said strips having overlapping relatively wide beveled portions cemented together to form a wide skived joint joining said strips at a point on the side of the counter well above said flange whereby both pieces of material at opposite sides of said joint form part of the side walls of the counter, the overlapping edge of the flexible upper strip being at the outer side of the counter.
